COMBINED DOOR-HINGING, DOOR-CHECKING, AND DOOR-HOLDING DEVICE

Rudolph I. Schonitzer, Shaker Heights, Ohio

Original application August 2, 1940, Serial No. 349,888. Divided and this application August 21, 1943, Serial No. 499,749

8 Claims. (Cl. 16—141)

1

This invention relates to combined door-hinging, door-checking and door-holding devices, the use with a door and its supporting structure of a device embodying the present invention (1) enabling said door to be hinged (by parts which are concealed when the door is closed) on its supporting structure, it being understood that one or more other hinge means generally will be used for the complete hinging of said door; (2) enabling the opening movement of said door to be checked or arrested when said door reaches the position desired for its fully open position; and (3) enabling said door to be releasably held or retained against closing from a predetermined open position, such as the fully open position of said door.

The present invention has for its general objects the provision of a device of the character described by which two or all three of the aforesaid functions may be effectively accomplished, the construction of such device and the arrangement of its parts being such that said device may be inexpensively manufactured and easily assembled with a door and its supporting structure.

Although the field of use of the present invention obviously is not limited to automobile doors, devices embodying such invention are particularly useful therewith, as will hereinafter appear.

More specific objects of the present invention are in part obvious and in part will appear more in detail hereafter.

The present invention will be readily understood from the following description of one embodiment thereof as used with an automobile door, reference being had to the accompanying drawings in which.

Fig. 1 is a longitudinal horizontal sectional view through the hinge edge portion of an automobile door and a corresponding portion of the automobile body on which said door is hinged by the use of one form of device embodying the present invention, the view being on the line 1—1, Fig. 4, and the door being in its closed position;

Fig. 2 is a view similar to Fig. 1, on the line 2—2, Fig. 3, with the door in its fully open position, the position in which it is releasably held or retained by such device;

Fig. 3 is a longitudinal vertical sectional view, on the line 3—3, Fig. 2;

Fig. 4 is a longitudinal vertical view, partly in elevation and partly in section, on the line 4—4, Fig. 1;

Fig. 5 is a detail vertical sectional view, on the line 5—5, Fig. 1;

2

Fig. 6 is a detail vertical sectional view, on the line 6—6, Fig. 2;

Fig. 7 is a top plan view of the housing of this form of device;

Fig. 8 is an elevation of the inner side portion of said housing, as viewed from the line 8—8, Fig. 7; and

Fig. 9 is an elevation of the rear portion of said housing, as viewed from the line 9—9, Fig. 8.

Before the present invention is described in detail, it is to be understood that such invention is not limited to the details of construction or the specific arrangement of parts herein illustrated or described, as the invention obviously may take other forms. It also is to be understood that the phraseology or terminology herein employed is for the purpose of description and not of limitation.

In the accompanying drawings, wherein is illustrated one form of device embodying the present invention, the reference numeral 18 designates a generally hollow sheet metal automobile door, such as is now in general use, and of which door only the hinge edge portion is here shown; and 19 designates the automobile body portion (hereinafter termed a body pillar) on which said door is hinged by the use of said device, it being understood that other hinge means (not here shown) generally will be used in conjunction with the present device for the complete hinging of said door on said body pillar.

As best shown in Figs. 1 and 2, the device constituting the herein illustrated embodiment of the present invention includes a hinge leaf 20 of the so-called goose neck form, one end of said hinge leaf being pivotally secured to or associated with the body pillar 19 and the other end of said hinge leaf being rigidly or immovably secured to or associated with the door 18. As a result, said door not only is supported on said body pillar (and in the appended claims, said body pillar is designated as a supporting structure for the door structure hinged thereon) but also, is free to swing about its hinge axis (to be later referred to) between its fully closed position, as in Fig. 1, and its fully open position, as in Fig. 2, all as will be readily understood.

As here shown, the rigidly secured end portion 21 of the hinge leaf 20 lies within the hinge edge portion of the door 18 (the hinge edge wall 22 of said door being provided with a suitable opening 23 to receive such end portion of said hinge leaf) and is screwed or otherwise immovably secured to the sheet metal inner side wall 24 of said door, said door being provided, as is usual, with a suit-

able trim panel or the like (not shown) by which its inner side wall 24 is desirably covered. For the pivotal connection of the other end 25 of said hinge leaf to the body pillar 19, a suitable sheet metal housing, illustrated in Figs. 7, 8 and 9, is here utilized, said housing being arranged within said body pillar and being welded or otherwise rigidly secured thereto.

Although said housing may take various forms, as will be readily understood, the one here utilized is of generally C shape in plan view (see Figs. 1, 2 and 7) and comprises a generally horizontal top flange 26, a corresponding bottom flange 27 and a generally vertical wall by which said top and bottom flanges are connected in spaced relation. For the rigid securing of said housing within and to said body pillar, the spaced inner and outer front portions 28 of the vertical wall of said housing (which portions here engage the sheet metal hinge edge wall 29 of said body pillar on opposite sides of the opening 30 with which such body pillar wall is provided for the reception of the hinge leaf 20) are welded or otherwise immovably secured to said wall, and the inner side portion 31 of said vertical housing wall (which here lies alongside the sheet metal inner side wall 32 of said body pillar) are welded or otherwise immovably secured to such side wall. If desired, of course, a one-piece housing may be utilized, but for economy in manufacture, the present housing includes two sheet metal members which, when connected together, give the housing its generally C shape. As here shown, the outer channel-shaped end portion of the inner housing member projects within the inner channel-shaped end portion of the outer housing member, and the overlapping flanges of such telescopically related end portions are welded or otherwise immovably connected together.

Extending through suitable apertures 33 in the outer side portion of the top and bottom housing flanges 26 and 27 is a pintle 34, on which is pivotally mounted, between said housing flanges, the end 25 of the hinge leaf 20, the effect of which is to locate the goose neck portion of such hinge leaf almost entirely within the generally C-shaped housing of the body pillar when the door 18 is in its closed position, as clearly shown in Fig. 1 and as will be readily understood. If desired and as here shown, the outer side portion of such housing, to which the hinge leaf 20 is pivotally connected by means of the pintle 34, may have the corresponding portions of its flanges 26 and 27 suitably reenforced and hence made more rigid, which is, of course, particularly desirable if the two housing members heretofore referred to are made of relatively light gauge sheet metal. The reinforcing member here utilized for such purpose is of generally U-shape in vertical section, the generally parallel leg portions 35 of said member lying between and alongside the outer side portions of the housing flanges 26 and 27 and the front connecting portion 36 of said reinforcing member lying alongside the outer front portion 28 of the generally vertical housing wall, as clearly shown in the accompanying drawings.

Pivotally secured to an intermediate portion of the goose neck hinge leaf 20 and extending rearwardly therefrom is an arm 38, the arm here shown being of metal and of generally flat form. For the connection of said arm to it, said hinge leaf is here provided intermediate its ends with a pair of inwardly extending, generally parallel

ears 39, between which the front end of said arm is located and to which it is pivotally connected by means of a rivet or like fastening member 40. For the extension therethrough of the arm 38, the rear portion 41 of the generally vertical housing wall is provided with a suitable opening, such as the generally horizontal slot 42, the housing wall portion 41 being here shown as substantially normal to the generally parallel inner and outer side walls 32 and 43 of the body pillar 19, as best shown in Figs. 1 and 2.

During opening movement of the door 18, the arm 38 is pulled forwardly by the hinge leaf 20, the movement of said hinge leaf at such time being clockwise, (as viewed in Figs. 1 and 2) and during closing movement of said door, said arm is pushed rearwardly by said hinge leaf, the movement of said hinge leaf being then counter-clockwise, as will be readily understood. In order to check or arrest the opening movement of said door, when it has been swung to the position desired for its fully open position, such as the position of said door in Fig. 2, a suitable abutment is here provided on the rear end portion of the arm 38, said arm abutment having cooperative engagement, for such purpose, with any suitable abutment of the body pillar 19. Inasmuch as the present body pillar abutment is of rigid or immovable character, as will herein-after appear, the arm abutment here utilized is a bumper member 45 of rubber or rubber-like material, the resiliency of which enables the final opening movement of the door 18 to be yieldingly checked or arrested when said bumper member is brought into cooperative engagement with the body pillar abutment, all as will be readily understood. To retain the bumper member 45 on the arm 38, so that it cannot slide rearwardly therealong when it cooperatively engages the body pillar abutment, a cotter pin 46 (secured to said arm back of or to the rear of said bumper member) is here utilized, a sheet metal washer 47 being interposed between said cotter pin and said bumper member, if desired and as here shown.

As pointed out in my prior United States Patent No. 2,043,976 for a Combined door-holding and door-checking device, it is quite desirable to releasably hold or retain an automobile door in its fully open position whenever it is moved thereto, and for the effective accomplishment of that result, the device constituting this embodiment of the present invention includes one or more retaining parts for retaining cooperation with one or more retainable parts of the arm 38 when the door 18 is in its fully open position. Although such retaining and retainable parts may take various forms, those utilized in this particular embodiment of the invention are of the general form disclosed in my co-pending United States patent application for Combined door-checking and door-holding devices, application Serial No. 221,570, filed July 27, 1938, now Patent No. 2,291,412 of July 28, 1942.

As clearly shown in Figs. 1, 2 and 3, the device constituting this first embodiment of the present invention includes two retaining parts in the form of elongated rollers 50, arranged within a generally flat sheet metal casing 51 and lying on opposite sides of the arm 38, said casing having aligned slots for the extension therethrough of said arm and being riveted or otherwise rigidly secured to the rear portion 41 of the generally vertical housing wall, the slots of said casing being in alignment, of course, with the housing

wall slot 42. For resiliently pressing said rollers into engagement with the upper and lower faces of the arm 38, leaf springs 52 are here utilized, a pair of such leaf springs being effective upon each such roller for that purpose, as shown in Fig. 3.

For cooperation with the rollers 50, in the releasable retention of the door 18 in its fully open position whenever it is swung thereto, the arm 38 is here provided, adjacent to but spaced from its bumper member 45, with a set of three projections 53, which constitute the retainable parts of said arm, there being two such projections on the upper face of said arm and one such projection on the lower face thereof, as in my aforesaid application, Serial No. 221,570.

In this particular embodiment of the present invention, the rear wall of the roller casing 51 constitutes the abutment of the body pillar 19 for cooperative engagement with the arm bumper member 45 in yieldingly checking or arresting the opening movement of the door 18 whenever it is swung to its fully open position. As will be readily understood, just before said door reaches its fully open position, the arm projections 53 pass between the retaining rollers 50, and immediately thereafter said rollers move into positions behind such projections, under the influence of their leaf springs 52. The effect, of course, is the releasable retention of the door 18 in its fully open position, the rollers 50 being releasably confined between the arm projections 53 and the arm bumper member 45. Although the rollers 50 are pressed against the arm 38 with considerable force by their leaf springs 52, and although the height and inclination of the arm projections 53 are such as to insure the releasable retention of the door 18 in its fully open position whenever it is moved thereto, the leverage conditions which exist enable said door to be readily closed when desired, as will be readily understood.

One of the important features of the device constituting this embodiment of the present invention is the relationship which exists between the inner side wall 32 of the body pillar 19 and the hinge center A of the door 18 (the hinge center of said door being on the longitudinal axis of the pintle 34) and the pivot center B of the arm 38. In Figs. 1 and 2, the letter C designates a dot-dash line which passes through the door hinge center A and the arm pivot center B when the door 18 is in its closed or Fig. 1 position; and the letter D designates a dot-dash line which passes through such centers A and B when said door is in its fully open or Fig. 2 position. The dot-dash line designated by the letter E in Figs. 1 and 2 is a line which passes through the door hinge center A and which is substantially normal to the general plane of the inner side wall 32 of the body pillar 19, the general plane of such side wall, as that term is here used, being more or less upright plane which not only includes such side wall but which also extends therebeyond. From an examination of Figs. 1 and 2, it will be apparent that the angle x formed by the lines C and E is equal to the angle y formed by the lines D and E, and as a result, the arm pivot center B is substantially the same distance from the general plane of the body pillar inner side wall 32 in both the closed and fully open positions of the door 18. Inasmuch as the arm 38 is substantially parallel to the general plane of such body pillar side wall 32 when said door is in its closed position, such arm (which is guided in its reciprocating

movement by the retaining rollers 50) will likewise be substantially parallel to the general plane of such body pillar side wall when said door is in fully open position, as a comparison of Figs. 1 and 2 indicates.

Although the advantages of this construction and relationship of parts are obvious, some of the specific advantages thereof which may be here pointed out are (1) the securement of a maximum door retention effect with minimum effort by the door retaining parts; (2) the reduction to a minimum of oscillation of the arm 38, which is quite important in automobile body construction; and (3) the ability to have the arm 38 of straight, rather than of curved or longitudinally bent, form, as the use of a straight arm greatly increases the effectiveness of the door-checking and door-retaining functions of the device constituting this embodiment of the present invention, all as will be readily understood.

To those skilled in the art to which the present invention relates, other features and advantages of devices embodying such invention will be evident from the foregoing description of one such embodiment.

The present application is a division of my co-pending application for Combined door-hinging, door-checking and door-holding devices, Serial No. 349,888, filed August 2, 1940, United States Patent No. 2,343,810 having issued on such application on March 7, 1944.

What I claim is:

1. In a device of the character described, a hinge leaf for rigid securement to a door, a bracket for rigid securement to a supporting structure for said door, said hinge leaf being pivotally connected to said bracket, and an arm pivotally connected to said hinge leaf for movement in said supporting structure, the pivot connection of said arm being substantially the same distance from the general plane of the inner side wall of said supporting structure when said door is in its closed and its fully open positions.
2. In a device of the character described, a hinge leaf for rigid securement to a door and for pivotal securement to the supporting structure for said door, and a substantially straight arm pivotally connected to said hinge leaf for movement in said supporting structure, the pivot connection of said arm being substantially the same distance from the general plane of the inner side wall of said supporting structure when said door is in its closed and its fully open positions.
3. In a device of the character described, a hinge leaf for rigid securement to a door, a bracket for rigid securement to a supporting structure for said door, said hinge leaf being pivotally connected to said bracket, and a substantially straight arm pivotally connected to said hinge leaf for movement in said supporting structure, the pivot connection of said arm being substantially the same distance from the general plane of the inner side wall of said supporting structure when said door is in its closed and its fully open positions, the disposition of said arm being generally parallel with the general plane of the inner side wall of said supporting structure when said door is in its closed position.
4. A combined door-hinging and door-checking device, comprising a hinge leaf for rigid securement to a door, bracket means for rigid securement to and within the door supporting structure and to which bracket means said hinge leaf is pivotally connected, said bracket means having an apertured portion for substantially

normal disposition relative to the side walls of the door supporting structure, an arm extending through said aperture and pivotally connected to said hinge leaf, and an abutment on said arm outside of said bracket means for cooperation with an abutment of the apertured portion of said bracket means in determining the fully open position of said door, the pivotal axis of said arm when the door is fully closed and fully open being substantially the same distance from one of the side walls of the door supporting structure, with the result that said arm has minimum departure from straight line movement as the door opens and closes.

5. A combined door-hinging and door-holding device, comprising a hinge leaf for rigid securing to a door, bracket means for rigid securing to and within the door supporting structure and to which bracket means said hinge leaf is pivotally connected, said bracket means having an apertured portion for substantially normal disposition relative to the side walls of the door supporting structure, an arm extending through said aperture and pivotally connected to said hinge leaf, a pair of rollers carried by the apertured portion of said bracket means on opposite sides of the arm extending through said aperture, resilient means yieldingly maintaining said rollers in engagement with said arm, and means on said arm for cooperation with said rollers in releasably resisting closing movement of said door from a predetermined open position, the pivotal axis of said arm when the door is fully closed and when in such predetermined open position being substantially the same distance from one of the side walls of the door supporting structure, with the result that said arm has minimum departure from straight line movement as the door opens and closes.

6. A combined door-hinging, door-checking and door-holding device, comprising a hinge leaf for rigid securing to a door, bracket means for rigid securing to and within the door supporting structure and to which bracket means said hinge leaf is pivotally connected, said bracket means having a pair of side portions for disposition adjacent the side walls of the door supporting structure and connected by an apertured portion substantially normal to such side walls, an arm extending through said aperture and pivotally connected to said hinge leaf, a casing secured to the apertured portion of said bracket means adjacent said aperture, rollers carried by said casing, on opposite sides of the arm extending through said aperture, and resiliently maintained in engagement with said arm, means on said arm for cooperation with said rollers in releasably resisting closing movement of said door from a predetermined open position, and an abutment on said arm outside of said bracket for cooperation with said casing in determining the

fully open position of said door, the pivotal axis of said arm when the door is fully closed and fully open being substantially the same distance from one of the side walls of the door supporting structure, with the result that said arm has minimum departure from straight line movement as the door opens and closes.

7. A combined door-hinging and door-checking device, comprising a hinge leaf of goose-neck form for rigid securing to a door, bracket means for rigid securing to and within the supporting structure for said door, said bracket means comprising two channel members shaped to jointly provide in plan view a U-shaped structure and connected with their channels facing the U-shaped opening thus provided and having their side walls at the top and bottom of the structure, said hinge leaf being pivotally connected to the side walls of one of said bracket members and the base of the other bracket member having an apertured portion substantially parallel with the hinge edge wall of the door supporting structure, an arm extending through said aperture and pivotally connected to said hinge leaf, and an abutment on said arm cooperable with an abutment of said bracket means to check or arrest further opening movement of the door when said door reaches a predetermined open position.
- 10 8. In a device of the character described, a hinge leaf for rigid securing to a door and for pivotal securing to the supporting structure for said door, and a substantially straight arm pivotally connected to said hinge leaf for movement in said supporting structure, the angle formed by a line extending through the pivot axes of said hinge leaf and said arm when the door is closed and a line extending through said pivot axes when the door is fully opened being divisible
- 15 35 40 45 into two equal parts by a line substantially normal to the inner side wall of the door supporting structure and extending through the hinge leaf pivot axis, whereby oscillation of said arm as it moves back and forth during opening and closing movements of the door is reduced to a minimum.

RUDOLPH I. SCHONITZER.
